RIP STRIP REMOVING DEVICE

Charles E. Bletsch, Highland Park, Ill.

Application March 27, 1957, Serial No. 648,847

2 Claims. (Cl. 220—52)

This invention is concerned generally with a device for opening packages, more particularly sealed packages of the type having a rip strip thereon.

Many commodities are packaged in cans having rip strips thereon for breaking the seals and opening the cans. Coffee is a common, everyday commodity that is packed in such a can, and is well known to everyone. However, there are many more commodities or substances packaged for sale or storage in such cans.

In opening such cans, a small key is associated with an extending tab on the side of the can, and the key is twisted to wind up a strip of metal which tears or rips off the side of the can. Unfortunately, it is often difficult to maintain the winding strip in the form of a spiral of constantly increasing diameter, but with no change in axial dimensions.

Quite frequently, the strip will run off one end or the other of the part that has been previously wound, resulting in a conoidal formation with the remaining portion of the strip to be torn off substantially at the apex of the cone. This often renders it impossible to rip the strip off any farther, and the part of the strip that has been wound up erroneously must be straightened out and re-wound. This is a rather dangerous operation, since the torn edges of the strip are extremely sharp, and are quite likely to cut the person attempting this operation. Furthermore, it is extremely difficult to cause the strip thereafter to wind up properly. Even when the strip does wind properly, there is still a danger of being cut by the sharp edges thereof.

Accordingly, it is an object of this invention to provide a device for removing the rip strip from a can without any danger to the operator, and insuring proper winding up of the strip at all times.

It is another object of this invention to provide a device for tearing the rip strip from a can which device engages the can at widely spaced points and is supported and stabilized thereby.

Yet another object of this invention is to provide a device for tearing the rip strip from a can, which device is supported partially by the hand at locations spaced a substantial distance from the operating area, and wherein the device is operated from entirely above the can, thereby eliminating danger of injury to the operator.

Other and further objects and advantages of the present invention will be apparent from the following description when taken in connection with the accompanying drawings wherein:

Fig. 1 is a perspective view of the device as used on a can;

Fig. 2 is a top view thereof;

Fig. 3 is an exploded perspective view of the operating parts thereof;

Fig. 4 is a vertical sectional view as taken along the line 4—4 in Fig. 2;

Fig. 5 is a fragmentary bottom view partly in section as taken along the line 5—5 in Fig. 4; and

2

Fig. 6 is a detail similar to a portion of Fig. 5 and showing the parts in a different position of operation.

Referring now in greater particularity to the drawings, there is shown a rip strip removing device identified generally by the numeral 10, and including a Y-shaped frame 12 having a stem 14 and a pair of branch arms 16. A block 18 is provided beneath the outer end of each arm, and may be held in place by any suitable fastening means 20 such as screws or rivets. Each block 18 is provided 10 on its undersurface with a plurality of arcuate grooves or guides 22 of different radii. These grooves are designed to fit over the upper bead 24 of a can 26, such as a coffee can. Which one of the grooves will receive the bead depends upon the diameter of the can. Generally speaking, the inner two grooves will receive the rim of a relatively small can, while the outer two grooves of the two blocks will receive the bead of a relatively large can. Intermediate size cans will have their beads received in the intermediate bead grooves, as will be apparent. In 20 the illustrative example, there are three grooves in the under surface of each block 18. However, this number can vary widely within the scope of the invention.

At the outer end of one of the arms 16, the rearmost arm with the stem 14 extending to the right as in Figs. 25 1 and 2, there is provided an upwardly extending and curved finger piece or grip 28, held in place by the fastening means 20.

The stem 14 is enlarged at the outer end as at 30, and is provided with a longitudinal slot 32 having arcuate ends 34 and 36 respectively located toward the arms and toward the outer end of the stem. A wind-up crank 30 mechanism indicated generally by the numeral 37 is mounted within the slot 32, and serves to wind-up or tear off the rip strip 39 of the can 26. The crank mechanism includes a two piece bearing 38 comprising a lower disk 40 having a raised, diametrical substantially rectangular section 42 thereon, with an upstanding threaded boss 44 surmounting the raised section 42. The boss 44, the raised section 42, and the disk 40 are provided with 35 an axial bore 46. The rectangular section 42 is received in the stem recess 32, with the upper faces 48 of the disk 40 bearing against the underside of the leg 14, and with the threaded boss 44 projecting above the leg 14. The two piece bearing 38 also includes a ring 50 which fits 40 over the threaded boss 44 and against the upper face of the raised portion 42, bearing lightly against the top of the leg 14. A nut 52 is threaded on the upper end of the boss 44, and holds the two pieces of the bearing 38 together.

A hollow shaft 54 is journaled within the bearing 38, and includes an integral, radially extending circumferential flange 56 received in a recess 58 in the underside of the lower part of the bearing 38, whereby to limit upward movement of the shaft 54. Adjacent the upper 55 end of the shaft, which end is immediately above the threaded boss 44 of the bearing, there is providing a non-circular section 59, such as the hexagonal section shown. A corresponding non-circular aperture 60 in a crank arm 62 fits over the non-circular section 59, and a rotatable handle 64 is mounted on the outer end of the crank arm. A sheet metal member 66 is provided with 60 a central aperture 68 which is received over the threaded upper end 70 of the hollow shaft 54 extending above the non-circular section 59. This sheet metal section 66 comprises a circular body portion 72 having a radially outwardly extending section 74 of substantially 90° in extent, and terminated by upstanding ears or lugs 76. A nut 78 is threaded on the upper end of the extending 65 threaded portion 70 and clamps the sheet metal section 66 down against the top of the crank arm 62, thereby locking the sheet metal section to the crank arm, and 70

anchoring the crank arm in place on top of the hollow shaft 54.

A lock shaft 80 is rotatably mounted within the hollow shaft 54, and has an enlarged head 82 at the lower end thereof received in a counterbore 84 in the bottom of the hollow shaft 54. The head 82 is cylindrical at its upper portion, but at its lower portion is relieved as at 86 along a plane substantially parallel to a diametrical plane, but displaced so as to leave somewhat over half of a cylinder in a lower part of the head. Thus, the lower part of the head 82 forms a lock 88, and it will be observed that one edge of the lock 88 adjacent the relieved section 86 is relieved along an arc as at 90. The lower end of the hollow shaft 54 is provided with a longitudinal slot 92 adjacent the lock 88.

The upper end of the lock shaft 80 extends above the top of the hollow shaft 54, and a knurled knob 94 is secured thereon by means such as a set screw 96. Substantially opposite to the set screw there is a radially projecting pin 98 which extends above the segment 74 of the sheet metal section 72, and lies between the ears 76. The pin and ears thus limit the degree of rotation of the knurled knob 94, and hence of the lock 88.

It will be observed that the knurled knob 94 covers the circular or ring-like part 72 of the sheet metal section 66, and it further will be observed that the arcuate ends 34 and 36 of the slot 32 in the stem 14 are arcs of substantially the same radius as the bearing 38, whereby to form a close fit therewith at either end of the slot.

When it is desired to remove the rip strip from a can, as the rip strip 39 from the can 26, the device 10 is positioned across the top of the can as shown in Figs. 1 and 2, with the bead 24 of the can received in which ever ones of the arcs 22 of the blocks 18 are appropriate in accordance with the diameter of the can. At the same time the crank structure 37 is slid radially inwardly or outwardly of the can in the slot 32 of the stem 14, also in accordance with the diameter of the can, and the slot 92 in the bottom of the hollow shaft 54 is slipped over the end of the rip strip 39 with the lock in the position shown in Fig. 5. The knurled knob 94 at this time has the pin 98 thereon abutting the ear 76 limiting its clockwise direction of rotation, as viewed from above. The knob is then rotated through substantially 90° to bring the pin against the ear 76 limiting rotation in the counterclockwise direction. This turns the lock 88 from the position shown in Fig. 5 to that shown in Fig. 6, thereby wedging the end of the rip strip between the wall of the hollow shaft 54 and the lock 88. It will be appreciated that the relieved corner 90 of the lock aids in bending the inner end of the rip strip to the proper position. The device is then held as shown in Fig. 1, with the index finger of the left hand engaging the finger piece 28, and the thumb engaging the can and the outer end of the other arm 16. The remaining fingers on the left hand may ride lightly against the side of the can to stabilize the can. The crank handle 64 is grasped by the right hand, and the crank is rotated in a clockwise direction. This causes the rip strip 39 to roll up around the outside of the hollow shaft 54 adjacent the lower end thereof, the can correspondingly rotating about its own axis and sliding beneath the blocks 18 and the under surface of the bearing 38 and the enlargement or collar 56 on the hollow shaft 54.

Inasmuch as the resting of the bearing 38 and of the collar 56 on the top of the can bead insures against up or down movement of the crank structure, it is impossible for the rip strip to roll up in any manner other than

in a spiral of constantly increasing diameter and without any variation in axial direction. Accordingly, the rip strip is rolled up and torn off of the can in an absolutely perfect manner. At the same time, it is impossible for the operator to cut himself, since the left hand is positioned at a substantial distance from the point of operation, and since the right hand is at all times maintained above the top of the can.

The specific embodiment of the invention as herein shown and described is for illustrative purposes only. Various changes in structure will no doubt occur to those skilled in the art, and are to be understood as forming a part of the invention insofar as they fall within the spirit and scope of the appended claims.

The invention is claimed as follows:

1. A device for removing the rip strip from a can comprising a Y-shaped frame having a pair of arms and a stem, guide means adjacent the ends of said arms for supporting said frame on the top of a can, a rotary member, means mounting said rotary member on said frame adjacent the end of said stem for rotation and for movement transverse of its axis longitudinally of said stem, said rotary member being adapted to project downwardly past the edge of the can, cam means on said rotary member adapted to secure a rip strip to said member, means on said member for rotating said rotary member whereby to wind the rip strip from a can, and a finger piece extending upwardly adjacent the end of one of said arms for aid in manually locating the device, said finger piece being concave away from the other arm.

2. A device for removing the rip strip from a can comprising a frame, means on said frame for supporting said frame on a can, a rotary hollow cylindrical member carried by said frame and adapted to project downwardly past the edge of a can in the vicinity of a rip strip thereon, means on said rotary member adapted to secure a rip strip to said member, and means on said member for rotating said member to wind the rip strip from the can, said rotary member having a longitudinal slot in the sidewall thereof, and securing means comprising a cam element rotatable within said member in a locking direction and reversely in an unlocking direction, said element having an arcuate surface with a relieved leading portion in the dissection of locking rotation to initially engage the rip strip and said arcuate surface being spaced from the inner surface of the cylindrical member and progressively approaching the inner surface of said cylindrical member in a trailing direction therefrom whereby to clamp a rip strip inserted through said slot in surface contact against the inner surface of said cylindrical member adjacent said slot.
